US00D901560S

(12) **United States Design Patent** (10) **Patent No.:** **US D901,560 S**
(45) **Date of Patent:** **** Nov. 10, 2020**

(54) **REFRIGERATOR**

(71) Applicant: **SAMSUNG ELECTRONICS CO., LTD.**, Suwon-si (KR)

(72) Inventors: **Hyunsoo Kim**, Seongnam-si (KR); **Youngmin Park**, Seoul (KR)

(73) Assignee: **SAMSUNG ELECTRONICS CO., LTD.**, Gyeonggi-do (KR)

(**) Term: **15 Years**

(21) Appl. No.: **29/676,077**

(22) Filed: **Jan. 8, 2019**

(30) **Foreign Application Priority Data**

Jul. 9, 2018 (KR) 30-2018-0031539

(57) **CLAIM**

The ornamental design for a refrigerator, as shown and described.

DESCRIPTION

FIG. 1 is a front perspective view of a refrigerator, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 2;

FIG. 10 is an enlarged view of the encircled portion in FIG. 4; and,

FIG. 11 is an enlarged view of the encircled portion in FIG. 6.

The even-dash broken lines depict portions of the refrigerator that form no part of the claimed design. The dot-dash broken lines represent boundaries of the claimed design and form no part thereof. The dot-dot-dash broken lines encircling enlargement portions of the refrigerator form no part of the claimed design.

1 Claim, 11 Drawing Sheets
